Attorney

UNITED STATES PATENT OFFICE.

RUDOLF H. HOWE, OF WOODWARD, ALABAMA.

MUSICAL INSTRUMENT.

Application filed March 29, 1926. Serial No. 98,097.

My invention relates to a new and improved type of musical instrument which contemplates the use of a drum as a resonating body having associated therewith a 5 number of strings which are adapted to be played by hammers, picked, or, if desired, bowed.

My invention contemplates stretching the strings across the drum and supporting 10 them by one or more bridges resting on the drum head, the preferable arrangement of bridges providing one bridge for each end of the strings, but, where desired, intermediate bridges may be used to produce a 15 stringing somewhat similar to the dulcimer or cymbalon. This arrangement makes possible the production of an instrument having a drum quality of tone and yet having a sufficiently larger scale compass to permit 20 the playing of melodies thereon and it contemplates utilizing various types of drums with varying numbers of strings, so that instruments with only a few notes of definite pitch can be provided for special pur- 25 poses or instruments with a larger number of strings and a larger range of scale can be provided and such instruments may be adapted to be played in any of the manners above referred to.

30 My invention contemplates the provision of strings singly or in sets and the tuning of the strings singly or in unison.

My invention further contemplates the cross bracing of the drum head with a strut 35 to resist the tension of the strings.

My invention further comprises the novel details of construction and arrangements of parts, which in their preferred embodiment only are illustrated in the accompanying

40 drawings; in which:

Fig. 1 is a plan view; and

Fig. 2 is a cross-sectional view taken on the line 2—2 of Fig. 1, showing a base drum equipped with a typical arrangement of 45 strings to convert it into a musical instrument according to my present invention.

Similar reference numerals refer to similar parts throughout the drawings.

I have illustrated my invention in connection with a base drum having a shell 1, a 50 bottom drum head 2 and a top drum head 3, the drum shell being provided with leg supports 4 and with marginal drum head tension elements 5, all in accordance with standard practice. It is to be understood, 55 however, that this type of drum is merely

illustrative of any drum since my invention is capable of adaptation to and use with any drum type of musical instrument. In order to convert the drum into the new and improved type of instrument contemplated in my invention, I mount on diametrically opposite sides of the drum shell string anchor blocks 6 and 7 which may be attached to the shell in any suitable manner and on the block 6 I mount a string anchor 7^a to which a series of strings 8, 8^a, 8^b, and 8^c are attached. At their other ends these strings are connected to tuning posts 9 adjustable to be turned by keys 10 mounted in the anchor block 7. It will be understood that any well known and available means for mounting and tuning the strings may be substituted for that shown, which is merely illustrative of one suitable arrangement.

In order to withstand the strain on the drum shell due to the action of the strings, I brace the shell with a strut 11 running parallel with and midway of the strings and suitably connected to the shell at points preferably opposite the center of the anchor blocks.

I provide for all of the strings and bridges 12 in order that they may be supported on the drum head as a resonating body. The arrangement of the strings, their grouping and the number shown is susceptible of wide variation. I have shown the strings 8 free of intermediate bridges; the strings 8^a having one intermediate bridge 13; the strings 8^b having two intermediate bridges 14; and the strings 8^c having three intermediate bridges 15. My arrangement thus contemplates the use of one string or a set of strings for each note.

Having constructed the instrument in the manner described and tuned the strings, it may be played by striking the strings with a hammer, by picking, or by bowing them according to the quantity of tone desired to 100 be produced, and in each case a new and distinct musical tone will result from the employment of the drum as a resonating body for the strings.

Though I have described with great particularity the details of the embodiment of the invention herein shown, it is not to be construed that I am limited thereto, as changes in arrangement and substitution of equivalents may be made by those skilled 110 in the art without departing from the invention as defined in the appended claims.

Having thus described my invention, what I claim as new and desire to secure by Letters Patent, is:—

- 5 1. A new type of musical instrument, comprising a drum having a drum head, a string mounted under tension across the drum head, and bridge means on the drum head supporting said string.
- 10 2. The combination with a drum having a drum head, of a plurality of strings, means to mount said strings across the drum head, and bridges supporting said strings on the drum head as a resonating body.
- 15 3. A musical instrument according to claim 2, in which the bridges are arranged at each end of the strings.
4. A musical instrument according to claim 2, in which the bridges are arranged at each end of all of the strings and at in-

termediate points under one or more of the strings.

5. The combination with a drum having a drum head and a drum shell, of diametrically opposite string anchors on the shell, a plurality of strings, means to mount said strings on said anchors, and bridges supporting said strings on the drum head.

6. The combination with a drum having a drum head and a drum shell, of diametrically opposite string anchors on the shell, a plurality of strings, means to mount said strings on said anchors, bridges supporting the strings on the drum head, and a cross brace for the drum shell interposed to withstand the strain of the strings.

In testimony whereof I affix my signature.

RUDOLF H. HOWE.
